VIBRATO PRODUCING MEANS FOR
MUSICAL INSTRUMENTS

Erving F. Gerlat, Racine, Wis.

Application September 22, 1944, Serial No. 555,221

1 Claim. (Cl. 84—189)

1

This invention relates to musical instruments and has as its general object the provision of means for imparting a vibrato quality to the tone of a musical instrument such as a piano.

Another object of this invention is to provide a device capable of imparting a vibrato quality to musical instruments, which is especially applicable to vertical pianos and when applied greatly improves the appearance of the instrument.

Another object of this invention is to provide a device of the character described which may be constructed in various sizes for application to instruments other than pianos and also to loud speakers, particularly of the type employed in connection with electric guitars and similar musical instruments.

A further object of this invention is to provide a device of the character described which is simple and readily applied to a piano or other instrument with which it is to be used.

With the above and other objects in view, which will appear as the description proceeds, this invention resides in the novel construction and arrangement of parts substantially as hereinafter described, and more particularly defined by the appended claim, it being understood that such changes in the precise embodiment of the herein-indisclosed invention may be made as come within the scope of the claim.

The accompanying drawings illustrate several complete examples of the physical embodiment of the invention constructed in accordance with the best modes so far devised for the practical application of the principles thereof, and in which:

Figure 1 is a perspective view illustrating the manner of applying the device of this invention to a vertical piano;

Figure 2 is a cross-sectional view taken through Figure 1 on the plane of the line 2—2;

Figure 3 is a top plan view of the vibrato producing device per se;

Figure 4 is a view illustrating the application of this invention to a horizontally strung piano;

Figure 5 is a bottom view of the installation shown in Figure 4;

Figure 6 is a side view with a part broken away and in section illustrating the application of this invention to a loud speaker; and

Figure 7 is a front view of the device shown in Figure 6.

Referring now particularly to the accompanying drawings, in which like numerals indicate like parts, the numeral 5 designates a vertical

2

piano of any conventional type, which, as is customary, is equipped with a sounding board 6 at the back thereof.

The device of this invention, indicated generally by the numeral 7, is applied to the back of the piano and when in position preferably covers the entire back thereof. Essentially the device 7 consists of an open faced chamber formed by a curved upright wall 8, end walls 9, 10 and a top wall 10. The top wall 10 has a plurality of ports 11, which, together, comprise an outlet.

When in position overlying the back of the piano, where it is held in any suitable manner, 15 as by hooks 12 on the piano and brackets 13 on the side wall 9, the sounding board or back of the piano in general cooperates with the walls of the chamber to define an air column, the outlet or space through which the sound waves move 20 to issue from ports 11.

The chamber should fit tightly against the back of the piano and preferably, though not necessarily, a felt packing strip or the like is provided along the vertical and bottom edges of the 25 chamber to seal the juncture between the back of the piano and the edges of the open face of the chamber.

In the upper portion of the chamber is a rotatable butterfly valve 14. This valve extends 30 from end to end of the chamber and is of a size to substantially wholly close the air passage when in a transverse position thus blocking the air column. Consequently, by rotation of the valve 14 the air column is intermittently interrupted to 35 impart a vibrato quality to the tone of the piano.

Rotation is preferably imparted to the butterfly valve by a small electric motor 15 mounted within the chamber and drivingly connected thereto by a silent belt drive 16. The motor 15 is 40 adapted to be controlled by the operator or player by means of a switch and control cord not shown.

Where the device of this invention is to be applied to a horizontally strung or so-called "grand" piano, it is mounted under the sounding 45 board, as shown in Figure 4, with the outlet ports 11 facing the side of the piano. Obviously, of course, the shape of the chamber must be somewhat altered to have it fit the underside of such a horizontally strung piano, but in its essential 50 characteristics the device is identical with that illustrated in Figures 1, 2 and 3.

In the case of a horizontally strung piano, it is preferable, however, to install a barrier of insulation material over the strings as indicated at 55 17 in Figure 4. This insures the major portion

of the tone being dispelled downwardly by the sounding board and through the vibrato producing device.

The application of the invention to loud speakers, as shown in Figures 6 and 7, is substantially the same as that employed in conjunction with a vertical piano excepting that the unit is of smaller size and made to fit the front of the cabinet or housing 18 in which the speaker is mounted.

From the foregoing description, taken in connection with the accompanying drawings, it will be readily apparent to those skilled in the art that this invention provides a novel manner of imparting a vibrato quality to a musical instrument such as a piano, which ordinarily does not possess this characteristic, and that the device of this invention is simple, readily applied and when in position on a vertical piano greatly improves the appearance of its back.

What I claim as my invention is:

An attachment for upright pianos to improve the appearance of the back thereof and to impart a vibrato tone to pianos equipped with the

attachment, comprising: a shallow box-like housing opening at its front and having a height and width substantially corresponding to the height and width of the piano for which the attachment is intended; means for attaching the housing to the back of the piano with no portion of the attachment projecting over or to the sides of the piano so that the back wall structure of the piano closes the open front of the attachment by contact with the side and top and bottom edges of the housing walls at said open front thereof, whereby the attachment covers and conceals the back of the piano and cooperates therewith to define a substantially upright tonal passage, said housing having an upper transversely extending wall portion thereof provided with a tonal opening acting as an outlet for said tonal passage; a rotatable valve extending transversely across said tonal passage beneath the tonal opening to intermittently block sound waves moving upwardly along the back wall of the housing towards said tonal opening; and means inside the box-like housing for rotating the valve.

ERVING F. GERLAT.
